ATTORNEYS

UNITED STATES PATENT OFFICE.

ERNEST FLAGG, OF NEW YORK, N. Y.

HINGE CONSTRUCTION.

Application filed March 27, 1923. Serial No. 628,084.

To all whom it may concern.

Be it known that I, ERNEST FLAGG, a citizen of the United States, and a resident of the city of New York, borough of Manhattan, in the county and State of New York, have invented a new and Improved Hinge Construction, of which the following is a full, clear, and exact description.

This invention relates to a new and improved form of hinge. An object of the invention relates to the provision of means whereby a hinge plate or member or similar device is more effectively connected to a support, such as a door or a door jamb, so that the load to be carried by the bracket or hinge member is more effectively borne thereby.

Another object is to provide a hinge member which is more efficient and economical than those now in common use.

A further object is to provide a hinge in which a minimum of metal is used but which is yet capable of bearing greater strains than the hinges now in use.

A still further object is to provide a hinge or bracket member portions of which connect with a support, such as a door or a door jamb, and are fastened thereto in a plane at right angles to the direction of thrust of the load to be borne thereby.

Hitherto, hinge plates and similar articles of hardware have been associated with surfaces with which they co-operate by means of screws with the plates bearing flat against said surfaces. In the case of door hinges particularly, the hinge plates have been laid flat against the vertical faces of the doors and the door jambs and attached thereto by screws so that in this case the entire weight of the door is borne by the screws, since they are the only elements of the hinge unit which extend into the door.

It is one of the many operations of this invention to provide a hinge plate, or the metallic portion of similar articles of hardware, which will extend into the material of the surface with which it is being associated, such as a door or door jamb, and thereby directly aid in bearing the load to be borne, rather than placing this heavy weight on a few screws. In other words, the large surface of the metallic plates of the hinge are utilized to directly bear the weight of the door or similar devices to be supported. To this end, I provide hinge members in

the form of flat plates which extend into the wood of the door and the jamb.

The invention is illustrated in the drawings, of which—

Figure 1 is a section taken on the line 1—1 of Fig. 2;

Fig. 2 is a partial front elevation of a hinge construction;

Fig. 3 is a section taken on the line 3—3 of Fig. 1;

Fig. 4 is a plan view of one of the hinge plates; and

Fig. 5 is a section through a corner of the door.

The form of the invention shown in the drawings is a preferred form, although it is understood that modifications in the construction and arrangement of the parts and in the character of the materials used may be adopted without departing from the spirit of the invention.

It will be understood, of course, that the application of this idea may vary and is not at all restricted to the use of the invention in the construction and application of hinges, but wherever it is desired to fasten a plate or bracket or similar device to a support, this same principle of connection can be adopted.

The preferred form of the invention, which I have shown in the drawings, involves its use in the form of door hinges. As shown, the invention comprises a pair of plates 1 and 2 provided with apertured extensions 3 and 4 adapted to overlap with their apertures in alinement and connected together by any suitable means, such as a rivet or bolt 5.

The plates primarily are of the form shown in Fig. 4 and may be cast or stamped out of metal. The lug portion of each plate extends substantially diagonally from one corner thereof to the opposite side of the plate and is rolled up as shown in Figs. 1 and 2 to form a tube, the edge of which is preferably rolled up, as designated 6 in Fig. 4.

With respect to the insertion of this hinge plate unit into a door or jamb, or the insertion of a similar construction into any supporting wall, I first bore a hole 10 into said surface near one edge thereof, such as 11, and then I cut a saw slot from said edge 11 into the hole or bore 10 connecting therewith. It will be seen that having the

plate body portion with a tubular member formed along one edge, this can be forced into the door, the tubular member extending into the hole 10 and the body portion of 5 the plate extending into the slit formed in the end of the door. It will be observed that the slot cut into the door and connecting with the hole 10 is cut diagonally into the door toward one corner thereof; likewise 10 on the door jamb; and that the plates 1 and 2 have an edge 7 adapted to lie flush with the end surface of the door and the jamb, and an inclined edge 8 adapted to lie along the bottom of the diagonal saw cut. These 15 plates are also provided with projecting prongs 9 which are extended into the wood of the door and jamb to hold the plates from slipping out of the slots.

The entire device is firmly secured to the 20 door and jamb by passing screws 13 and 14 through the tubular members on the plates into the wood or body of the door and jamb, as shown particularly in Fig. 1.

It will, consequently, be seen that the 25 other hinge plate is fastened into the jamb or corresponding surface in an identical manner, and when the door is related with the jamb in the proper manner the two extensions 3 and 4 will overlap and the bolt 5 can connect the same so that they may form hinge surfaces, the one pivoted or turning on the other. It will be noted that the weight of the door on the plate 2 is taken by 30 said plate at right angles to its surface. It will be, furthermore, noted that the weight of the door on the plate 2 is supported by the jamb by reason of its connection with plate 1 which is disposed in a plane at right angles to the reaction between said plate and the jamb. There are no screws provided 35 which bear the weight of any article supported and which tend to be sheared off. By reason of the ample surface provided to directly support the door and be introduced 40 into the article to be supported, a smaller area of hinge plates can be used to support a given load. This is for the reason that practically the entire body portion of the plate is used to directly support the load by contrast therewith. Furthermore, by having 45 the tubular formation on one portion of the plate insertable within a bore or hole on the article to be supported, it is next to impossible to withdraw said plate from the article to be supported, especially after it has been latched in place as above described. In other words, the hinge does not depend upon screws but the weight of the door or 50 other article is supported on the flat of the plates, the hinge being attached both to the door and to the jambs, in a more logical and scientific manner, the bearing being firmly on the end grain of the wood. Thus, little metal is used while great strength and 55 ease of operation is secured.

It will, therefore, be seen that by merely boring a hole near the edge of the door on the jamb and making a diagonal saw cut, this plate and tubular member, which can be stamped out of a single piece of metal 70 and very easily formed to shape, can be slipped into place and held temporarily therein, at least by tapping it with a hammer to drive the prongs 9 into the wood, and can be held permanently in place by inserting 75 the screws above mentioned.

This device is very economical to manufacture, will bear the weight of the door in a most efficient manner because the weight comes at right angles on this relatively large 80 plate surface and is borne thereby and not by any screws. There is practically no shearing effect in this sort of hinge.

What I claim is:

1. A hinge which includes a hinge plate 85 portion adapted to be inserted into a supporting body portion at right angles to the surface thereof, the entire hinge plate portion adapted to be embedded in the body portion so that the entire surface of the 90 plate portion contributes to the support of the body portion.

2. A device for fastening hinge members and the like to a support, which includes a plate portion, a tubular member on said 95 plate portion, said tubular member and a portion of the plate adapted to be inserted respectively into a tubular bore and a slot in the support, and means for fastening the tubular member and the plate portion there- 100 in.

3. The combination with a supporting body portion having a bore therein adjacent one edge and a slot extending into said bore from said edge, of a plate adapted to 105 project into said slot, a tubular member formed on said plate adapted to extend into said bore, and means for fastening the tubu- lar member in the bore.

4. The combination with a supporting 110 body portion having a bore adjacent one edge and a diagonal slot or saw cut made in the body portion in a plane passing through the bore, said slot connected with said bore, of a plate having a portion to 115 lie in the slot or saw cut, a prong on said plate to project into the wood beyond the bottom of the slot, a tubular member formed on said plate to extend into said bore, and screw means adapted to pass through the 120 tubular member into the body of the wood to hold the plate permanently in position.

5. The combination with a supporting body portion having a bore adjacent one edge and a diagonal slot or saw cut made 125 in the body portion in a plane passing through the bore, said slot connected with said bore, of a plate having a portion to lie in the slot or saw cut, a prong on said plate to project into the wood beyond the 130

bottom of the slot, a tubular member formed on said plate to extend into said bore, and screw means adapted to pass through the tubular member into the body of the wood 5 to hold the plate permanently in position, said plate provided with an apertured extension to form one member of a hinge.

6. The combination with a supporting body portion having a bore adjacent one 10 edge and a diagonal slot or saw cut made in the body portion in a plane passing through the bore, said slot connected with said bore, of a plate having a portion to lie in the

slot or saw cut, a prong on said plate to project into the wood beyond the bottom 15 of the slot, a tubular member formed on said plate to extend into said bore, and screw means adapted to pass through the tubular member into the body of the wood to hold the plate permanently in position, 20 said plate provided with an apertured extension to form one member of a hinge, said plate and extension lying in a horizontal plane at right angles to the action of rotation of the door.

ERNEST FLAGG.
